FOLDING DRESSING TABLE

Charles T. De Puy, Brighton, N. Y., assignor to
 Trimble Nurseryland Furniture, Inc., Rochester,
 N. Y., a corporation of New York

Application December 27, 1940, Serial No. 371,933

5 Claims. (Cl. 311—78)

This invention relates to a folding bath stand and dressing table of the general type that is conventionally used for bathing and dressing infants, and has for its object to afford a simple structure that can be economically manufactured and is especially adapted for use as a toy or doll bath stand and dressing table, although the features are not necessarily confined to such purposes and may be incorporated in a full sized structure intended for infants' use.

More particularly, the invention has for its object to afford a construction employing a collapsible cross-legged support or stand constructed in such a manner that a flexible dressing table cooperates to hold the leg frames in collapsed or folded relation when the device is not in use, the flexible table for this purpose being connected to a table frame that swings downwardly in advance of the front leg frame and is fastened thereto while the dressing table is drawn tightly around the top rails of the leg frames and is held in substantially fixed relation to the rear top rail.

In a more specific aspect, the invention comprehends a flexible dressing table fastened at its front edge to a table frame and extending thence rearwardly over the front and rear top rails respectively and downwardly to a point beneath the rear top rail, its rear or lower edge being secured to a rigid member that is connected to a resilient retaining means or spring which in turn is secured to a portion of the front leg frame, so that the retaining means functions to hold the dressing table in its upright or vertical position and also to maintain it in a taut condition over the rear top rail when the parts are folded, while at the same time the relation of the retaining means to the table is such as to exert no tendency to elevate the table frame when the latter is in horizontal or operative position.

To these and other ends, the invention consists in the construction and arrangement of parts that will appear clearly from the following description when read in conjunction with the accompanying drawings, the novel features being pointed out in the claims following the specification.

In the drawings:

Fig. 1 is a rear elevation of a structure made in accordance with a preferred embodiment of the invention and showing the flexible table in horizontal or operative position;

Fig. 2 is an end elevation of the same;

Fig. 3 is a vertical sectional view of the same;

Fig. 4 is a similar view, with the table in its upright position;

Fig. 5 is a front elevation showing the parts in folded relation;

Fig. 6 is a plan view showing a modified form of dressing table, and

Fig. 7 is a partial vertical sectional view of the same.

Referring more particularly to the drawings, in which like reference numerals refer to the same parts throughout the several views, 1 and 2 designate the front and rear leg frames, provided with the top rails 3 and 4 respectively, between which is secured the collapsible tub 5. The leg frames are pivotally connected at 6 to permit their folding, while 7 and 8 designate bottom rails of the front and rear leg frames respectively. 9 designates a screen guard mounted upon a suitable wire frame that is attached to the upper ends of the legs of the rear leg frame. The structure thus far described is of conventional form, and the novel features having to do with the dressing table and the manner in which it functions to hold the leg frames folded will now be set forth in detail.

10 11 designates a table supporting frame which may be formed of wire or otherwise, the side members of the table frame being pivotally mounted on the rear leg frame 2 and preferably swingingly supported on the rear top rail 4 in the manner shown. The table frame is positionable over the front leg frame when in horizontal position and includes a front portion 12 that is located parallel to and forwardly of the front top rail when the dressing table is in horizontal relation.

15 20 25 30 35 40 The dressing table is indicated at 13 and may be of canvas or other flexible material, that is connected at its forward edge to the front portion 12 of the table frame by means of a hem formed in the fabric. When in horizontal position, the flexible table 13 extends from the front portion 12 of the table frame over the front top rail 3 upon which the flexible table rests, thence over the rear top rail 4, and downwardly for a distance somewhat below the rear top rail 4.

45 50 55 The flexible table is held taut in horizontal or operative position and in folded or collapsed position preferably by resilient retaining means, and to this end the flexible table carries at its rear lower edge a rigid member or bar 14, secured in the hem of the fabric, and connected to the rigid member 14 is a spring 15 which extends thence downwardly and is connected to the bottom rail 7 of the front leg frame. The spring 15 thus acts to hold the leg frames in spread or operative relation and to draw the rear edge of the flexible table downwardly and stretch the fabric table in a more or less taut condition over the top rails upon which it is supported.

60 65 70 75 80 85 90 95 The relation of the spring 15 to the table is such that it has no tendency to elevate the table from its horizontal position, and when it is desired to raise the table, the front portion 12 of the table frame must be manually lifted to swing the table to its upper or vertical position. When

in vertical position, the flexible table rests against the screen guard 9 and the table is held in such position by the spring 15, the primary function of which is to hold the leg frames in folded relation through the instrumentality of the flexible table in the manner that will now be described.

When it is desired to fold the stand, the upper ends of the leg frames are moved toward each other and then the table frame is swung downwardly until the front portion thereof lies parallel against the front leg frame, the table frame being held in such lowered position by means of the fastening devices or hooks 16 carried by the legs of the front leg frame and adapted when turned to engage the front portion of the table frame. When the parts are in this folded position, the leg frames are held together by the engagement of the fastening devices just described with the front portion of the table frame and the spring 15 which exerts sufficient tension on the flexible table to draw it tautly around the rear top rail and thus maintain the top rails of the leg frames in close relation to each other.

It is possible to omit the spring 15 and the downwardly extending portion of the flexible table, by attaching the rear edge of the latter to the top rail of the rear leg frame, as shown in the modified form of Fig. 6. With such an arrangement, if the canvas or similar fabric does not have sufficient yieldability to permit it to stretch and hold the leg frames in folded relation, the flexible table can be constructed of suitable elastic material so that it will readily give sufficiently to permit it to stretch around the forward top rail when the table frame is in its lowered position, and also maintain a smooth taut surface when in its horizontal or operating position.

While the invention has been described with reference to the particular structural embodiment shown, it is not confined to the details herein set forth, and this application is intended to cover any modifications or changes coming within the purposes of the improvement and the scope of the following claims.

I claim:

1. The combination with a foldable support comprising front and rear pivotally connected leg frames each of which includes a longitudinally extending top rail, of a table frame pivotally mounted on the rear top rail and positionable horizontally over the front leg frame, said table frame having a front portion located parallel to and forwardly of the front top rail when in horizontal position, a flexible table connected to said front portion of the table frame, said flexible table resting on the front top rail and extending rearwardly therefrom when the table frame is in horizontal position and thence around the rear top rail and downwardly to a point beneath the latter, a rigid member carried by and extending longitudinally of the flexible table at its rear lower edge, fastening means holding the table frame in lowered vertical position against the front leg frame when the support is folded, and yieldable retaining means connecting said rigid member with a portion of the front leg frame to hold the flexible table taut and the leg frames together when in folded position.

2. The combination with a foldable support comprising front and rear pivotally connected leg frames each of which includes a longitudinally ex-

tending top rail, of a table frame pivoted to the rear leg frame and positionable horizontally over the front leg frame, said table frame having a front portion located parallel to and forwardly of the front top rail when in horizontal position, a flexible table connected to said front portion of the table frame and resting on the front top rail when in horizontal position, means acting to hold the flexible table in substantially fixed relation to the rear top rail, and fastening means holding the table frame in lowered vertical position against the front leg frame when the support is folded with the flexible table stretched taut from the rear top rail around the front top rail and to the front portion of the table frame.

3. The combination with a foldable support comprising front and rear pivotally connected leg frames each of which includes a longitudinally extending top rail, of a table frame pivoted to the rear leg frame and positionable horizontally over the front leg frame, said table frame having a front portion located parallel to and forwardly of the front top rail when in horizontal position, a flexible table connected to said front portion of the table frame and held in substantially fixed relation to the rear top rail, and fastening means acting to hold the table frame in lowered vertical position against the front leg frame when the support is folded, the flexible table being stretched taut over the front top rail and acting to hold the leg frames in folded relation.

4. The combination with a foldable support comprising front and rear pivotally connected leg frames each of which includes a longitudinally extending top rail, of a table frame pivoted to the rear leg frame and positionable horizontally over the front leg frame, said table frame having a front portion located parallel to and forwardly of the front top rail when in horizontal position, a flexible table connected to said front portion of the table frame, said table being of elastic material and having its rear edge secured to the rear top rail, and fastening means acting to hold the table frame in lowered vertical position against the front leg frame when the support is folded, the flexible table being stretched taut over the front top rail and acting to hold the leg frames in folded relation.

5. The combination with a foldable support comprising front and rear pivotally connected leg frames each of which includes a longitudinally extending top rail, of a table frame pivoted to the rear leg frame and positionable horizontally over the front leg frame, said table frame having a front portion located parallel to and forwardly of the front top rail when in horizontal position, a flexible table connected to said front portion of the table frame and extending rearwardly therefrom and around the rear top rail when the table frame is in horizontal position, a rigid member carried by and extending longitudinally of the rear edge of the flexible table, a screen guard secured to the rear leg frame and acting to limit upward movement of the table, and a spring connecting said rigid member with the front leg frame, said spring acting to hold the table in vertical position against the screen guard without being effective to move the table away from its horizontal position.

CHARLES T. DE PUY.
